UNITED STATES PATENT OFFICE.

LEOPOLD AUERBACH, OF NEW YORK, N. Y.

DESIGN FOR A BOX.

SPECIFICATION forming part of Design No. 31,585, dated October 3, 1899.

Application filed August 12, 1899. Serial No. 727,071. Term of patent 14 years.

To all whom it may concern:

Be it known that I, LEOPOLD AUERBACH, of the city of New York, borough of Manhattan, in the county of New York and State of New York, have produced a new and original 5 Design for a Box, of which the following is a full, clear, and exact description.

Reference is to be had to the accompanying drawings, forming a part of this specification, 10 in which similar characters of reference indicate corresponding parts in all the figures.

Figure 1 is a top view of a box, showing my design. Fig. 2 is a side view, and Fig. 3 is a section on the line 3 3 of Fig. 1.

The design for a box consists of a cylindrical body having on its top the profile representation of a man formed in relief, around which is a circle of bead-like projections, and on the outer surface of the body is a number of annular channels, the spaces between the 15 channels being vertically ribbed.

I claim—

The design for a box herein shown and described.

LEOPOLD AUERBACH.
